(57) **CLAIM**

The ornamental design for a mirror lamp, as shown and described.

DESCRIPTION

FIG. 1 is a front perspective view of a mirror lamp, showing my new design;

FIG. 2 is a right side view thereof;

FIG. 3 is a left side view thereof;

FIG. 4 is a front view thereof;

FIG. 5 is a rear view thereof; and

FIG. 6 is a top view thereof;

FIG. 7 is a bottom view thereof; and,

FIG. 8 is an enlarged view of the callout of FIG. 1, at a slightly rotated angle from that shown in FIG. 1.

The dash-dot-dash lines of FIG. 1 illustrate the portion of FIG. 1 that is shown in the enlarged view of FIG. 8. The mirror lamp shown herein has a light source housed into the peripheral border.

1 Claim, 8 Drawing Sheets
